(57) **CLAIM**

The ornamental design for an LED grow light, as shown and described.

DESCRIPTION

FIG. 1 is a perspective view of a LED grow light showing my new design;

FIG. 2 is a front view thereof;

FIG. 3 is a rear view thereof;

FIG. 4 is an enlarged left view thereof;

FIG. 5 is an enlarged right view thereof;

FIG. 6 is a top view thereof;

FIG. 7 is a bottom view thereof;

FIG. 8 is an enlarged view of the selected portion 8 in FIG. 1; and,

FIG. 9 is an enlarged view of the selected portion 9 in FIG. 2.

The broken lines shown in the figures depict portions of the LED grow light that form no part of the claimed design. The additional broken lines encircling the enlarged views in FIGS. 1-2 and 8-9 are for annotative purposes only and form no part of the claim thereof.
